EDWARD P. ROCHE, OF BATH, MAINE, ASSIGNOR OF ONE-HALF
TO E. A. POTTER, OF SAME PLACE.

Letters Patent No. 95,381, dated September 28, 1869.

IMPROVED CHAFING-IRON FOR WAGONS.

The Schedule referred to in these Letters Patent and making part of the same.

To all to whom these presents shall come:

Be it known that I, E. P. ROCHE, of Bath, in the county of Sagadahoc, and State of Maine, have invented a new and useful Improvement in Chafing-Irons for Carriages; and do hereby declare the following to be a full, clear, and exact description thereof, due reference being had to the accompanying drawings, making part of this specification, and in which—

Figure 1 is a perspective view, and

Figure 2, a horizontal section of my invention.

The invention comprising the subject-matter of this patent has reference to that portion of a wheeled vehicle known as the chafing or "rub-irons," and which, as is well understood, are employed for the purpose of protecting the body of the carriage from injury by the tires of the wheel.

The original plan adopted was to apply a stationary or immovable bar of iron to the carriage-body, against which the periphery of the wheel abraded; but in practice it was found that the wheel, in many instances, would run under the iron bar, and raise or overturn the carriage.

To overcome this difficulty, a roller, mounted upon a shaft, supported in suitable bearings, has latterly been adopted, and it is to this particular class of "rub-irons" that my present invention has especial reference.

Previous to the introduction of my invention, the rub-iron has been placed with its general length parallel, or thereabouts, to the sides of the carriage-body. As the tire of the wheel impinges against the iron, under these circumstances, at an angle, whether a fixed iron or a roller is adopted, the periphery of the wheel slides upon the iron, and is forced backward to such an extent as to produce, in many instances, "dishing" of the wheel, and, in some instances, its ruin; consequently, great caution must be exercised in turning a carriage in a small circle, for the oblique pressure upon the roll has the effect not only of straining the spokes, but of producing such a powerful endwise thrust upon the roll, as well as upon its axis, as to entirely prevent its rotation.

The invention herein described is intended to obviate these existing faults, in a simple manner, which it accomplishes by placing the rub-iron, whether a bar or roller, at an angle to the body of the carriage, and at right angles to the plane of the wheel, at its point of incidence with the iron.

In the drawings, to which allusion has before been made as accompanying this specification, and which illustrate my invention, *a* represents a bent metallic bar, for receiving and supporting the roll, which is shown at *b* as turning a pin or rod *c*, extended through it loosely, and confined within the bar *a* in a suitable manner, such bar, in practice, being affixed to the carriage-body in such manner that the axis of the roll and the plane of the wheel, when in contact, shall be at right angles to each other.

I have found, in careful practice, that with the rub-iron disposed at right angles to the plane of the wheel,

in case of turning the vehicle in a small space, both the rear wheels are raised off the ground, and, to some extent, moved with the rear of the carriage-body over it, thus enabling the carriage to turn in a circle of much less radius than at present, and, owing to absence of danger from overturning, in much less time.

As the roll is free to revolve upon its axis at all times, and as it is to be made preferably of chilled iron, wear upon the parts ensues very slowly.

It may be found, in some classes of vehicles, impossible to place the roll directly at right angles to the plane of the impinging-wheel, but only approximately thereto.

Under such circumstances, I have devised a duplicate protection against friction upon the end of the roll next the rear of the carriage, at which point, if any, it will occur.

One of such devices consists in disposing between the end of the roll and the adjacent face of the bar *a*, one or more spherical anti-friction balls, as shown at *d d*, in the drawings.

The second device, shown in Figure 3 of the drawings, consists in the adoption of a spring, *f*, of an elastic material, coiled wire, or other suitable form or material, disposed within a recess, *g*, made in the end of the roll, and with its opposite end pressing against a washer or collar, *u*, interposed between the end of the roll and the bar *a*, the outer face of the said washer being convex.

The disposition of the roll, as before mentioned, that is, at right angles to the plane of revolution of the wheel, is productive of several advantages: It removes friction and wear to a great extent from the parts. It permits a vehicle to be turned in a much less time, and in almost absolute safety.

I would state that practice has demonstrated that the rapid revolution of the roll has the effect of throwing off, by centrifugal force, any dirt which would otherwise adhere to it and find its way to the arbor upon which it revolves.

I would also remark that I have contemplated enlarging the central part of the bore of the roller, and inserting therein a sponge or other absorbing-material, saturated with a suitable lubricating-oil or compound.

Having thus described the nature and advantages of my invention or improvement,

What I believe to be novel and original with myself, and desire to secure by Letters Patent of the United States, is as follows:

I claim a chafing-roller, applied to the body of a vehicle in such a manner as to present its axis of revolution at right angles to the plane of revolution of the wheel at the point of incidence of the two, when combined with the anti-friction balls *d d*, the spring *f*, and the bar *a*, as and for the purposes herein described.

EDWD. P. ROCHE.
